UNITED STATES PATENT OFFICE.

ROBERT W. TAYLOR, OF KALAMAZOO, MICHIGAN.

DIRECTION-INDICATOR FOR MOTOR-VEHICLES.

1,817,240.

Specification of Letters Patent. Patented Sept. 30, 1919.

Application filed June 21, 1918. Serial No. 241,195.

To all whom it may concern:

Be it known that I, ROBERT W. TAYLOR, a citizen of the United States, residing at Kalamazoo, in the county of Kalamazoo and State of Michigan, have invented certain new and useful Improvements in Direction-Indicators for Motor-Vehicles, of which the following is a specification.

This invention is an indicator and has 10 special reference to a direction indicator for vehicles.

One object of this invention is the production of a direction indicator wherein a signaling element in the form of a hand is pivotally supported and is connected to means 15 for swinging the hand to an operative position when desired.

Another object of this invention is the production of a signaling element having a 20 danger indicating lamp carried thereon, the lamp casing being provided with a lens for projecting rays of light onto the indicating element when the same is swung to an operative position.

25 Another object of this invention is the production of a direction indicator or a signal which consists of a casing having a solenoid carried therein, the core of the solenoid being connected by links to the indicating element, whereby when the core is retracted by 30 the solenoid, the links will shift the indicating element to an operative position.

A still further object of this invention is the production of a signaling device which 35 consists of a casing having a front wall provided with a removable hood, whereby the hood may be removed for allowing free access to the operating elements carried upon the front wall.

40 Broadly stated, the invention consists of a casing having a front wall provided with a bottom, a hood slidably mounted upon said front wall, a solenoid carried by said front wall, a lamp carried upon said front wall 45 and provided with a bearing portion, an indicating element in the form of a hand movably mounted upon the bearing portion of the lamp, links connecting said indicating element to the core of the solenoid, whereby 50 the indicating element may be swung to operative or inoperative positions.

One practical form of construction and assembly of the present invention will be hereinafter described and is illustrated in 55 the accompanying drawing, in which—

Figure 1 is a front elevation of the signal,

as constructed in accordance with the present invention.

Fig. 2 is a central vertical section through 60 the signal.

Fig. 3 is a central horizontal transverse section through the signal, and

Fig. 4 is a fragmentary elevation of the rear portion of the signal, the hood being 65 removed from the front wall.

In the preferred embodiment of the present invention about to be described, it will be seen that the casing consists of a front wall 5 having a bottom 6 extending rearwardly therefrom and at right angles thereto. This 70 front wall 5 is provided with flanges 7 upon its side edges for gripping and releasably retaining the hood to be hereinafter described.

The gripping bar 8 is riveted as indicated 75 at 9 to the front wall 5 and has a jaw 10 formed thereon. The gripping bar 11 is also provided with a jaw 12 and this gripping bar 11 is fixed by a bolt and nut arrangement 13 to the bar 8, whereby the jaws 12 80 may grip a support 14, which of course may be a wind shield, or any other part of a vehicle upon which the indicating device is carried.

The bracket 15 is fixed as indicated at 85 16 upon the front wall 5 in the casing, as shown in Fig. 2. A solenoid 17 is supported upon this bracket and has a movable core 18 extending therefrom. The connecting link 19 has off-set ends as indicated at 20 and one 90 of the ends 20 is pivotally mounted as indicated at 21 upon the upper or outer end of the core 18. The draw link 22 is connected as indicated at 23 to the opposite end of the connecting link 19.

The front wall 5 is provided with an arcuate slot 24 formed therethrough adjacent its upper end, as shown in Fig. 4, and a screw 25 passes through the slot 24 and engages the arm 26 to be hereinafter referred to. 100

The lamp body 27 has a bearing portion 28 extending therefrom and projecting through the front wall of the housing of the casing and the nut 29 is carried upon the bearing 28, thus holding the lamp body 27 in 105 a set position.

The indicating element 30, which is in the form of a hand, as will be seen in Fig. 1 has a sleeve 31 rotatably or pivotally mounted upon the bearing 28, thus permitting the 110 indicator 30 to be swung to an active or idle position. The arm 26, hereinbefore referred

to, extends from the sleeve 31 and for this reason when this arm 26 is shifted, it is obvious the sleeve will be turned upon the bearing 28, thus holding the indicating 30 in an active position and permitting the same to move to an idle position.

The lamp 32 is carried by the lamp body 27 and has a casing 33 carried by the lamp body 27 extending therearound, it being noted that the casing 33 is provided with a lens 34, which is preferably of colored glass such for instance as red, thus giving a danger signal at night. The casing 33 is provided with a lens 35 carried by one side 15 thereof in alinement with the lamp 32, thus causing the rays of the light to be projected by the lens 35 to one side of the casing and upon the face of the indicating element 30 when the same is in a horizontal or operative position.

The hood 36 has side flanges 37 formed thereon and these flanges are releasably carried by the flanges 7 of the front wall 5. The hood 36 is substantially U-shaped in 25 cross section as shown in Fig. 3 and upon referring to Fig. 2 it will be noted that the upper end of the hood is closed adjacent the top edge of the front wall 5, thus preventing weather from beating into the interior 30 of the casing. The lower end of the hood 36 is open and the lower end bears upon the bottom 6 of the casing, thus protecting the contents of the casing from the weather.

It will be noted that a conductor cord 38 35 extends through the bottom 6 and has conductors 39 connected to the solenoid 17, while branch conductors 40 are connected to the lamp 32 in any desired manner. Thus it will be seen that when the circuit is closed 40 the lamp will be illuminated and also the solenoid 17 will be magnetized for operating the signal.

Under normal conditions, the signal will extend downwardly, although when it is desired to give a signal, the circuit may be closed to cause the solenoid to draw the core 18 thereinto. As the core 18 moves into the solenoid, the connecting link 19 will draw upon the draw link 22, thus causing the 45 screw 25 to move the arm 26. As this arm is moved, it will cause the sleeve 31 to swing the indicating element to an operative or substantially horizontal position, to give a signal. This movement on the part of the 50 indicating element 30 will cause the element to move into the direct path of the rays of light projected from the side lens 35 of the lamp, thus causing the indicating element to be illuminated. As soon as the circuit is 55 broken, the solenoid will be deenergized, thus allowing the weight of the indicating element 30 to draw upon the links and the

arms to move the core from the interior of the solenoid to the position shown in Fig. 4. When the solenoid is energized however, 65 it will draw the core thereinto as indicated in Fig. 2.

The foregoing description and the drawings have reference to what may be considered the preferred or approved form of my 70 invention. It is to be understood that I may make such changes in construction and arrangement and combination of parts, materials, dimensions, et cetera, as may prove expedient and fall within the scope of the 75 appended claims.

Having thus fully described my invention, what I claim as new and desire to secure by Letters Patent, is:—

1. In a device of the class described, the 80 combination of a casing whose front wall has an arcuate slot therein, a lamp body having a bearing carried by said front wall, an indicating element having a sleeve rotatably mounted upon said bearing, and an arm extending from said sleeve; of a solenoid in said casing, a screw connected to the core thereof and extending through the slot and connected to the arm, whereby when the solenoid attracts said core, said screw and 85 arm will bring said indicating element to a position in line with the rays of light projected from said lamp, and a hood carried upon said front wall to shield said lamp from the weather.

2. In a device of the class described, the combination of a casing consisting of a front wall having an arcuate slot therein, a lamp body having a bearing carried by said front wall, an indicating element having a sleeve 100 rotatably mounted upon said bearing, an arm extending from said sleeve, a solenoid carried by said front wall, a core extending from said solenoid, a connecting link having off-set ends connected to said solenoid, a 105 draw link connected to one of the off-set ends of said connecting link, a screw connected to the draw link and extending through the slot to be connected to the arm, whereby when the solenoids attract said 110 core, said link and arm will bring said indicating element to an operative position in direct line with the rays of light projected from said lamp, said slot permitting of movement of the screw connecting the arm 115 to the draw link, and a hood carried upon said front wall to shield said solenoid and lamp from the weather.

In testimony whereof I affix my signature in presence of two witnesses.

ROBERT W. TAYLOR.
